CLAIM

The ornamental design for a Christmas tree watering ornament, as shown and described.

DESCRIPTION

FIG. 1 is a front elevational view of a first embodiment of a Christmas tree watering ornament showing my new design, the rear elevational view being a mirror image thereof;

FIG. 2 is a left side elevational view thereof, the right side elevational view being a mirror image thereof;

FIG. 3 is a bottom plan view thereof;

FIG. 4 is a top plan view thereof;

FIG. 5 is a front elevational view of a second embodiment of a Christmas tree watering ornament showing my new design, the rear elevational view being a mirror image thereof;

FIG. 6 is a left side elevational view thereof, the right side elevational view being a mirror image thereof;

FIG. 7 is a bottom plan view thereof; and,

FIG. 8 is a top plan view thereof.
